UNITED STATES PATENT OFFICE

WILLIAM H. CRAP, OF PHILLIPSBURG, NEW JERSEY

ICE SANDAL

Application filed July 22, 1931. Serial No. 552,480.

My present invention has reference to a sandal which is primarily designed for use in the winter time, to prevent persons using the same from slipping on icy surfaces, although the improvement may be successfully employed by athletes or others whose tasks render them susceptible to slipping in the performing of their tasks or work.

A further object is the provision of a sandal which can be easily and conveniently arranged upon the shoe of the user, and effectively sustained from movement in any direction when so arranged.

A still further object is the provision of a sandal whose foot or body portion is constructed from a single piece of light but tough material and which is reinforced to effectively strengthen the same in a manner that will not impair but rather insure flexibility and which likewise will hold the sandal in proper shape and which also provides means for the reception of the shanks of removable calks, that insures the safe travel of the user over extremely slippery surfaces.

To the attainment of the foregoing the invention consists in the improvement herein-after described and definitely claimed.

In the drawing:

Figure 1 is a top plan view of the improvement.

Figure 2 is a side elevation thereof.

Figure 3 is a sectional view approximately on the line 3—3 of Figure 1.

Figure 4 is a plan view of one of the calks and the attaching element therefor.

As disclosed by the drawing the sandal 1 is of a shape to correspond with the sole of the shoe upon which the same is to be arranged. The sandal may be constructed of any desired material which is flexible, such for instance, as thick rubber, heavy cardboard having fabric reinforcements, of fabric of a desired strength and thickness, or of sole leather.

At the sides of its toe and heel portions the body of the sandal is formed with lateral extensions that afford straps 2—2, respectively, one of each of said straps carrying a buckle 3 whose tongue is passed through openings in the cooperating strap, and these straps,

of course, provide means whereby the sandal is strapped upon the shoe of the user. On its upper face the sandal 1, at its point from the toe, has secured thereto a substantially H-shaped metal plate. The central element of 65 this plate is indicated for distinction by the numeral 4 and the lateral ends by the numerals 5 and 6, respectively. The lateral extension 6 which is arranged below the sole nearest the instep portion of the sandal is 60 wider than the end 5 of the strip nearest the toe portion of the sandal. The H-shaped strip is fixed on the sandal in any desired or preferred manner and all of the parts provided thereby are formed with openings that 65 align with similar openings in the sandal. The openings in the lateral extensions 5 are arranged close to the end thereof and the opening in the central portion 4 is arranged approximately through the center thereof. 70 These openings have passed therethrough the shanks 16 of double headed rivets 7. The outer heads of the rivets afford anti-slipping elements. The rivets from their outer heads are provided with sockets 8 in which are received the headed shanks 9 of calks 10 which are V-shaped in side elevation and star-shaped in plan. The sockets 8 may be slotted to insure the passage of and the proper frictional engagement with the shanks when arranged therein.

At the rear of the H-shaped reinforcing plate there is secured on the upper face of the sandal the angle end 11 of another metal reinforcing plate. This plate has a downwardly 85 extending portion 12, and from thence is formed with a straight extension 13 which has its end formed with lateral extensions 14. All of the parts of this reinforcing plate are to be secured to the sandal by double headed 90 rivets 15, and the said reinforcing plates provide the sandal with instep and heel engaging portions when arranged on a shoe. The double headed rivets 15 that engage the laterally extending end 14 of the rear reinforcing plate have sockets which enter from their outer ends and these sockets are designed to removably receive therein the headed shanks of two of the calks 10. The rivets have been described as double headed, but this is not 95 100

an absolute necessity as the rivets may be of the ordinary type and have their shanks from their outer ends provided with sockets so that the upper faces of the calks will contact with the outer face of the sandal when their headed shanks are received in the sockets. This arrangement may, in fact, be found preferable.

The calks, of course, are of extremely hard metal and by the employment of a suitable implement, such as pinchers the same may be secured to the sandal or removed therefrom.

It is thought the foregoing description will fully and clearly set forth the construction and advantages of my improved device so that further detailed description will not be required.

Having described the invention, I claim:

A sandal comprising a body of yieldable material having integrally formed front and rear attaching straps, reinforcing metal plates at the front and at the rear of the sandal, the rear plate having a central portion which is bent upwardly and from thence arranged at an angle to form the under face of the sandal with a shoulder and with an angle portion, the shoulder designed to be arranged against the heel of the shoe of the user and the angle portion designed to contact with the shoe adjacent said heel portion, rivets securing the reinforcing plates to the sandal, said rivets being double headed and having sockets entering from their outer heads, and said sockets designed to receive therein and to be frictionally engaged by shanks on the heads of calks.

In testimony whereof I affix my signature.

WILLIAM H. CRAP.
